Primary Examiner — Kevin K Rudzinski*Assistant Examiner* — Amber J Rabie(74) *Attorney, Agent, or Firm* — Eric Karich; Karich & Associates(57) **CLAIM**

The ornamental design for a clothing wrap, as shown and described.

DESCRIPTION

FIG. 1 is a front elevational view of a clothing wrap, showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 shows the clothing wrap being worn by a person in a first configuration; and,

FIG. 8 shows the clothing wrap being worn by a person in a second configuration.

The broken lines shown in the drawings illustrate environment of the clothing wrap that forms no part of the claimed design.
